United States Patent Office.

CURTIS T. FORREST, OF SAN FRANCISCO, CALIFORNIA.

Letters Patent No. 101,359, dated March 29, 1870.

IMPROVEMENT IN WATER-CLOSET VALVES.

The Schedule referred to in these Letters Patent and making part of the same.

To all whom it may concern:

Be it known that CURTIS T. FORREST, of San Francisco, in the county of San Francisco and State of California, have invented certain new and useful Improvements in Valves to Water-Closets; and I do hereby declare that the following is a full and exact description of the same, reference being had to the accompanying drawings and to the letters of reference marked thereon.

My invention relates to certain improvements in water-closet valves and apparatus for regulating the same; and consists of a device automatic in its operation and that is not liable to easily get out of repair, and by which an effective cleansing of the basin of deposit is had with an economical use of water.

Referring to the drawings—

Figure 1 is a front elevation of such parts of a water-closet as are necessary to show the nature of my invention.

Figure 2 is a transverse section of the faucet or valve.

Figure 3 is a sectional view of the tank or reservoir.

Figure 4 is a sectional view of a device by which the plug of the faucet is prevented from sticking.

A represents the seat of the closet upon which the operator sits. This seat is provided with the usual perforations, (not shown in the drawings,) and beneath it is fixed, to the frame or casing B, the pan of deposit, provided with a trap in any improved manner.

The seat A is hinged at the back, and is prevented from opening to a greater extent than desired by means of the screw and eye-bolt shown at f.

D is the plug or valve, the axis of which is horizontal, and

E, the casing forming the faucet.

The apparatus is supplied with water by a pipe connected to the faucet by means of the female screw a.

The reservoir, fig. 3, is air and water-tight, and is to be secured in some convenient position at a suitable height above the seat. This reservoir is provided with an air-valve, consisting of a float, d, and stem s and casing g, and is connected with the faucet by means of a pipe and the female screws b b'.

The water is conveyed to the basin of deposit by means of a pipe connected to the faucet at c.

h is an oil-cup for lubricating the plug D, and connects, by means of the passage p, with the recess r.

From the seat A depends a strong arm, o, to which is riveted the end of the strap s.

The strap s passes from the end of the arm o over the circumference of the head of the plug D to the weight w, and back to a pin, x, in the plug or valve.

At the rear end of the valve is a screw, F, which operates against the plug and keeps it in place, and prevents binding or sticking in the seat.

The operation of this apparatus is as follows:

When the person takes a position on the seat A the action causes the weight w to rise, and motion is communicated to the plug D by means of the strap s, and the plug D is carried into the position shown in fig. 2, and the water enters at a and rushes through b and fills the reservoir, fig. 3, closing the float-valves s d g.

When the weight is removed from the seat A the weight w will descend, causing the seat A and valve D to resume their original positions, and thus cutting off the communication between a and b, and opening the communication between b and c, allowing the water from the tank, fig. 3, to run into and through the basin of deposit, and in this position the apparatus will remain until the next operator comes along.

Having thus described my invention,

What I claim, and desire to secure by Letters Patent, is—

1. The combination of the faucet D E, provided with the regulating-screw F, with the straps s and weight w, when arranged and operated as described, for the purpose set forth.

2. In combination with the above, an air-tight reservoir, having the float-valves s d g and stop f, as described, for the purpose set forth.

In witness whereof I have hereunto set my hand and seal.

C. T. FORREST. [L. S.]
